APPARATUS FOR ASSEMBLY OF MOUNTS

Elwood W. Schafer, Millburn, N. J., assignor to
 National Union Radio Corporation, Newark,
 N. J., a corporation of Delaware

Application December 20, 1943, Serial No. 515,066

4 Claims. (Cl. 29—25.19)

1

The present invention relates to apparatus for the assembly of multiple electrodes into a unitary structure, commonly termed a mount, in the fabrication of discharge devices, particularly radio tubes.

The practice followed in building up the mount structure of a multiple grid type radio tube requires at one stage of the assembly the insertion into a supporting mica of one end of the electrodes, which may be a cathode, first grid, second grid, third grid or beam plates and an anode, and then feeding the other ends of these electrodes individually into a second mica to make a unit assembly independent of the stem of the tube. All motion studies indicate that this "second mica assembly" or "top mica threading" has become a limiting operation in the high speed production of radio tubes. The correct breakdown of multiple operative mounting units is handicapped by the necessity of this second mica operation, and to obtain high group assembly production rates it is often necessary to employ two or three such operatives to keep up with preceding and following operations. This destroys the true "line-of-production" and results in an even higher loss of efficiency than that due to the extra operatives.

As tube structures grow more complicated; as more grids are used; and as tighter fits must be maintained between the grid legs and the mica holes to reduce microphonic effects the handicap imposed by the second mica assembly becomes more limiting. As greater group production rates are obtained by better motion study and breakdown of operations the more apparent becomes the effect of this one slow operation.

It is broadly an object of the present invention to provide a method of automatically aligning the projecting ends of work parts by the use of magnetic means, whereby the time element is reduced and the operation greatly simplified.

Another object of the invention is the provision of aligning and holding means of a magnetic character, i. e., either a permanent magnet or an electromagnet, designed to contact the work parts and hold the ends thereof in fixed position and relatively spaced, whereby the threading of supporting mica members over the projecting ends of the work parts is greatly facilitated.

Another object is the provision of a magnetic member terminating in a relatively thin blade designed to function as a gauge which may be moved into and out of engagement with the projecting ends of the work parts, whereby a precision operation necessary in making grid assembly is greatly facilitated.

2

Other objects relating to features of construction, manipulation of work parts, etc., will become manifest as the description proceeds.

Referring to the accompanying drawings:

Fig. 1 is a perspective view of a jig embodying the invention, the upper projecting ends of the electrode elements being held in alignment by magnetic means for threading of the top mica;

Fig. 2 is a view similar to Fig. 1, showing the top mica threaded on the electrode elements and the magnetic blade member withdrawn from the work parts;

Fig. 3 is an enlarged simplified diagrammatic view, partly in section, showing particularly the grid elements and including the top and bottom mica, constituting the supporting members of the general mount assembly; and

Fig. 4 is an enlarged plan view, partly broken away, of the comb-shaped edge of the magnetic blade member.

For a more detailed description, reference may be had to the drawings, more particularly Figs. 1 and 2. In illustrating my invention I have shown it embodied in an electromagnetically operated jig, but it will be appreciated that the same principles would apply if a permanent magnetic structure was used.

The jig member may constitute a super-structure supported from a base block 1, having inserted therein a post 2 over which fits a collar 3, adjustable vertically on the post 2 by means of a thumb screw 4. Carried at the top of the collar 3 is a supporting block 5. Mounted upon the upper face of the block 5 is a head block member 6, which is seated in a cut-away portion of the supporting block 5 and extends upwardly therefrom. The top surface of the head block 6 is provided with a counter-sunk recess 7, the general configuration of which corresponds to that of a mica 8, which is commonly oblong in shape. Well pockets 16, formed vertical in the block 6, are in spaced relation and in alignment with one another. The purpose and/or function of this arrangement will hereinafter be more fully described.

The block 6 is drilled and keyed transversely near the base thereof to provide an opening for a key-pin 9, the fit between the pin 9 and its opening being one of frictional engagement for means of adjustment. Carried upon the inner end of the pin 9 is a bracket structure 10, including a cross-bar member 11 which may be integral with an extending pole piece 12, the lower surface of which is inclined so as to form a sliding contact with a complementary inclined surface formed upon

the upper opposing edge of the block 5. When these inclined surfaces are brought into engagement by manipulation of the cross-bar 11, they constitute a firm support for the bracket structure 10, and also close the magnetic circuit by insuring sufficient contact area between these parts, as will be more fully understood from the following description.

The electromagnet 13 may be of the usual construction comprising a spool having heads 14, between which is wound a coil (not shown) upon a core terminating at its upper end in a pole piece carrying a blade member 15. The blade member 15 tapers outwardly to form a thin edge and is composed of magnetic material, such as iron. The front edge of the blade is provided with notches 17 formed in the magnetic material and these notches are alternated with sections 19 of non-magnetic material, such as brass. The depth and width of the notches closely correspond to the diameter of the projecting legs 18 of the electrode members, and the spacing of the notches 17 conform to the center-to-center of the holes provided in the mica pieces, thus insuring a snug fit of the legs 18 within the notches 17, whereby said legs are held in more perfect alignment and spaced relation so that precision fitting may be obtained between the mica holes and the electrode legs. It will be appreciated by those skilled in the art that the tighter the fit between the holes in the mica and the projecting legs 18, there is a corresponding reduction in undesirable micro-phonic effects caused by a loose fit between these parts.

It will be noted that having the sides of the notches of non-magnetic material insures that the projecting ends 18 of the electrodes easily fall into the notches, and are retained in place by the magnetic material; further, that by regulating the length the non-magnetic material is inlaid or extends into the magnetic material, there is provided a coarse but simple means for directing the effective magnetic force applied to the projecting electrode legs 18. It will also be appreciated some mount assemblies have projections on certain of the electrodes, as for example, the plate as shown in Fig. 2, which projections 21 are laterally spaced from the grid legs 18, thus requiring a comparatively deep cut or insertion in the blade 15 to accommodate such laterally spaced projections 21.

Variations of this character will occur for each type of grid assembly, and therefore a different jig set-up, by change in the blade 15, as well as change in the head block 6, will be required for changes in assembly structures, but the principle or mode of operation will be the same for the several grid assemblies.

Mounted in any suitable manner, as for example on the supporting block 5, is an electrical connector element 22 including a switch (not shown) and a pair of conductors 23 which carry the current for energizing the coil of the electromagnet, thus producing the magnetic field which magnetizes the blade 15. Normally the current is interrupted, but when desired, the circuit may be closed by manipulation of the control switch.

The method of assembly of the electrodes comprising a given mount, by the use of my jig, may be described as follows. By manipulating the cross-bar member 11, the electromagnet structure may be retracted or moved backwardly from the head block 6 as shown in Fig. 2. The reciprocal mounting of the pin 9 in the block 6 permits this adjustment. The mica 8, used in this step of

the assembly operations is usually designated as the "first mica," is then dropped into the recess 7 by the operative. The placement of the first mica is such that the holes therein automatically fall into alignment with the well pockets 16. In the grid structure illustrated schematically in Fig. 3, the central electrode may be the sleeve of an indirectly heated type cathode. Adjacent to the cathode sleeve, and concentrically arranged therewith, may be placed a plurality of grids, which may be designated generally as first, second, etc., grid, depending upon the grid structure undergoing assembly. On the outside of the grids may be inserted a pair of posts 24, to which may be secured the plate electrode, for example.

On the other hand, in the grid assembly shown in Figs. 1, 2, and 4, the cathode is of the directly heated type, which is inserted as a subsequent independent operation. The plate or anode which surrounds the grids, is provided with prongs 21 formed upon punched-out ears or extensions 20. To accommodate the projecting prong 21, the central tooth of the blade member 15 is cut deeper, as shown particularly in Fig. 4.

Regardless of the type of assembly, the feature of importance is that all of the electrodes are manually loaded into the "first mica," and upon the completion of the same, the magnetic structure is moved forward by operation of the cross-bar 11, so that the thin magnetic blade 15 is brought into operative position, i. e., with the notches 17 engaging the projecting legs 18 of the electrodes.

At this stage of the operation, the switch controlling the current through the electromagnet is actuated, thus completing the electric circuit which magnetizes the blade 15, resulting in the electrode legs 18 being automatically drawn into engagement with and firmly held within the notches 17. Since the legs are now properly held in spaced relation to the holes in the mica 8, the top or "second mica" is easily threaded upon the legs 18 by merely dropping the mica thereover.

With the placement of the "second mica" over the legs 18 of the electrodes, the current producing the magnetic field may be interrupted, thus de-magnetizing the blade 15 or the permanent magnetic circuit may be mechanically opened, by withdrawal of structure 10. This relieves the magnetic pull or attraction upon the projecting legs 18 and by manipulating the cross-bar 11, electromagnet 13 and component structure, may be moved rearwardly and out of engagement with the grid assembly. The operative is then free to remove the assembly from the head block 6. To facilitate this step in the operation, it will be noted that two opposing sides of the block 6 have been cut away to provide recesses 25, so that the fingers of the operative may be easily inserted underneath the first mica and the grid assembly withdrawn by an upper movement of the operative's hand.

It will be understood from the foregoing that for every change in the electrodes comprising a particular grid assembly, it will be necessary to change the head block 6 so as to accommodate the change in structure from one grid assembly to another. It may be noted at this point, that the depth of the several well pockets 16 is such that the projecting ends of the electrodes 18 limit the distance said electrodes may be inserted into the well pockets 16. In this manner, the distance the ends of the electrodes extend beyond the first or lower mica 8, is regulated at the time the electrodes are dropped into the well pockets. With

respect to regulating the amount of projection of the top of the legs 18 beyond the "second mica," the same may be accomplished by regulating the height of the head block 6. That is to say, if the jig was previously adjusted for the fabrication of a miniature grid assembly, and it is desired to change to a larger type of grid assembly, it will not only be necessary to use a different arrangement of the well pockets 16, but also a shorter head block 6 since the distance between the block 5 and the edge of the blade 15 is fixed. Because of this requirement, the head block 6 is made demountable from the supporting block 5.

It may be observed at this point that according to the construction and method of operation of my jig, it is no longer necessary to stagger the projecting ends of the electrodes so as to facilitate the insertion of these ends in the holes of the mica. That is to say, the support wires or posts for the electrodes may now be of equal length, thus saving in material and at the same time avoiding the inconvenience of making the electrode support wires of uneven lengths so as to produce a staggered relation therebetween.

As a matter of convenience for the operative, the grids super-structure is adjustable vertically on the post 2 so that by manipulating the thumb screw 4 the jig proper may be raised or lowered to bring the work parts on the most convenient level to suit a given operative.

I have found that by the use of my jig the operation of threading the top or second mica is greatly expedited and the operative performing this step in a line production unit can easily keep pace with the other operatives comprising the group.

Modifications and variations in the structure and/or method disclosed herein will suggest themselves to those skilled in the art. For example, it is obvious that in the place of using an electromagnet system, the blade 15 may be a permanent magnet. Further, in order to further facilitate the electrode legs 18 properly aligning themselves in the notches of the blade 15, the teeth of the comb portion of the blade may be tapered inwardly or slightly rounded off so that the openings of the notches 17 are widened and act as guiding means for the legs 18 to enter the notches. The notches may also be made V-shaped. It is therefore desired to cover all such modifications as come within the scope of the appended claims.

What is claimed is:

1. In a mount assembly jig, a head block for supporting a first mica in a recess formed in the block, said head block being provided with well pockets in spaced relation with respect to the center-to-center spacing of holes in the mica,

said well pockets being adapted to receive the projecting ends of electrode elements and function as a support for the electrodes during the assembly thereof into a mount unit, electromagnetic means associated with the head block including a core having a pole piece terminating in a blade member of magnetic material, the edge of said blade member having non-magnetic material alternated with the magnetic material, the magnetic portions of said edge being provided with notches, means for bringing the notches of the blade and the well pockets into alignment, and conducting means including a switch for the current producing a magnetic field which magnetizes the blade, whereby the projecting legs of the electrode elements are securely held in fixed position within the notches thus facilitating the threading of a second mica over said legs.

2. In a jig for assembling multiple electrode grid mounts, means for supporting one end of the electrodes in the same spaced relation with respect to holes of a first mica, means for aligning the opposite ends of the electrodes in correspondingly spaced relationship, and magnetic means for clamping the aligned free ends of the electrodes in said fixed relative position, whereby the threading of a second mica over the clamped ends of the electrodes is greatly facilitated.

3. The construction claimed in claim 2, where-
30 in the magnetic means includes a blade member of magnetic material terminating in a relatively thin comb edge, the teeth of said comb being of non-magnetic material and separated from one another by notched out alternate portions of the magnetic material.

4. In a mount assembly jig, means for holding a perforated mica disc, said holding means being provided with well pockets correspondingly spaced with respect to the perforations of the 40 mica and adapted to support the ends of electrodes projecting through said perforations, and magnetic means for clamping the unsupported ends of the electrodes in similarly spaced relationship to the supported ends of the electrodes, thus facilitating the threading of a second mica over the clamped ends of the electrodes.
